PLASTIC FLOOR SLAT

Theodor M. Box, 1108 Aileen Road,
Brielle, N.J. 08730

Filed June 15, 1972, Ser. No. 262,996

Term of patent 14 years

Int. Cl. D25—01

U.S. Cl. D13—1 J

FIG. 1 is an isometric view of the plastic floor slat;
FIG. 2 is an end view of the plastic floor slat;
FIG. 3 is a side view of the plastic floor slat;

FIG. 4 is a partial top plan view of the plastic floor slat; and

FIG. 5 is a cross-sectional view of the plastic floor slat taken along line 5—5 of FIG. 4.

I claim:

The ornamental design for a plastic floor slat, as shown.
